[57] CLAIM

The ornamental design for a programmable audio player, as shown and described.

DESCRIPTION

FIG. 1 is a perspective view of a programmable audio player, showing a preferred embodiment of our new ornamental design.

FIG. 2 is a front view of a programmable audio player, showing a preferred embodiment of our new ornamental design.

FIG. 3 is a right side view of a programmable audio player, showing a preferred embodiment of our new ornamental design.

FIG. 4 is a left side view of a programmable audio player, showing a preferred embodiment of our new ornamental design.

FIG. 5 is a top view of a programmable audio player, showing a preferred embodiment of our new ornamental design.

FIG. 6 is a bottom view of a programmable audio player, showing a preferred embodiment of our new design.

FIG. 7 is a back view of a programmable audio player, showing a preferred embodiment of our new ornamental design.

FIG. 8 is a reduced right side view thereof, shown in an alternate position.

FIG. 9 is a front view thereof; and,

FIG. 10 is a perspective view thereof.

The broken line showing of the charging unit in FIGS. 8-10 is for illustrative purposes only and forms no part of the claimed design.
